UNITED STATES PATENT OFFICE

2,088,173

BREAKDOWN-FIREARM

George S. Lewis, New Haven, Conn., assignor to
Winchester Repeating Arms Company, New Ha-
ven, Conn., a corporation of Maryland

Application July 10, 1935, Serial No. 30,599

1 Claim. (Cl. 42—40)

This invention relates to an improvement in breakdown-firearms, that is to say, that class of firearms in which a barrel-unit and a butt-unit are hinged together for relative pivotal movement.

More particularly, the present invention relates to the means by which the relative pivotal movement of the two firearm-units above referred to is limited in the direction of the breakdown or opening of the firearm.

One of the objects of the present invention is to provide a breakdown-firearm with superior means for checking the breakdown movement between the barrel- and butt-units thereof.

A further object is to provide a breakdown-firearm with simple, reliable and effective means for checking the relative pivotal movement between its two main movements in the direction of the breakdown or opening of the firearm.

With the above and other objects in view, as will appear to those skilled in the art from the following, considered in conjunction with the accompanying drawing and appended claim, the present invention includes all features disclosed therein which are novel over the prior art.

In the accompanying drawing:

Fig. 1 is a view in side elevation of a breakdown-shotgun embodying the present invention, but with the forestock in vertical, central-longitudinal section, and showing the butt- and barrel-units in their normal relative positions;

Fig. 2 is a broken view partly in side elevation and partly in vertical, central-longitudinal section, but showing the barrel-unit in its breakdown position;

Fig. 3 is a broken perspective view of the forward end of the frame;

Fig. 4 is a perspective view of the forestock-shoe; and

Fig. 5 is a broken perspective view of the rear portion of the forestock.

The particular breakdown-firearm herein chosen for illustration includes two major units pivoted together for relative pivotal movement. The rear unit of the firearm may, for convenience of description, be designated as the "butt-unit," and comprises in the main a frame 20 and a buttstock 21 rigidly secured to the said frame. The complementary front unit of the firearm, designated for convenience of description as the "barrel-unit," comprises in the main a barrel 22 and a forestock 23 removably secured to the under-side of the said barrel.

The forward portion of the frame 20 is of substantially U-shaped form in cross-section pro-

viding an upwardly-opening recess or pocket 24 receiving a rectangular barrel-coupling lug 25 forming a rigid feature of and depending from the under-side of the barrel 22 adjacent the rear end of the latter. The U-shaped forward portion of the frame 20 comprises complementary side-walls 26 and 27 (Fig. 3), a bottom-wall 28 and a relatively-short front-wall 29.

The forward edge of the barrel-coupling lug 25 is formed with a transverse forwardly-opening notch 30 the forwardly-facing semicircular wall of which engages and bears upon a fulcrum-pin 31 extending transversely through the frame 20 and forming a fixed feature thereof. Substantially all of the rear half of the central portion of the fulcrum-pin 31 is located rearwardly of the front-wall 29 of the frame 20, as clearly shown in Figs. 2 and 3.

The forward end of the frame 20 is shaped to form a cylindrically-contoured bearing-surface 32 having its central axis coinciding with the central axis of the fulcrum-pin 31 before referred to.

Conforming in curvature to and normally bearing against the bearing-surface 32 of the frame 20 is a forestock-shoe, generally designated by the numeral 33. The forestock-shoe just referred to comprises a forwardly-extending tang 34 having a vertical threaded bore 35, a depending tongue 36 and complementary upstanding side-prongs or ears 37—37, each of which latter terminates in a downwardly-and-rearwardly-extending hook-like stop-finger 38 providing a stop-abutment 39. The respective rear surfaces of the tongue 36 and the side-prongs or ears 37 merge together and are curved in a manner conforming to the cylindrically-contoured bearing-surface 32 at the forward end of the frame 20.

The upper surface of the forestock 23 is transversely shaped to conform to and snugly fit the bottom half of the barrel 22. The rear face of the said forestock 23 is milled or otherwise shaped to provide a vertically-curving recess 40 receiving the tongue 36 and the side-prongs 37—37 of the forestock-shoe 33, and resulting in the formation on the respective opposite sides of the said forestock, at the rear end thereof, of a pair of complementary ears 41—41 (Fig. 5) overlapping the adjacent side-surfaces of the frame 20 and partially covering the curved line on which the curved rear face of the forestock-shoe 33 engages with the similarly-curved forward end of the frame 20.

The central portion of the transversely-curved upper-face of the forestock 23 is cut away to pro-

vide a longitudinal pocket or recess 42 receiving the tang 34 of the forestock-shoe 33, before referred to. Secured to the under-face of the tang 34 of the forestock-shoe 33 is a forestock-retainer 43 engaging with a retaining-lug 44 depending from and forming a rigid feature of the barrel 22 at a point forwardly of the barrel-coupling lug 25 thereof.

The forestock-retainer 43, above referred to, 10 is secured to the under-side of the tang 34 of the forestock-shoe 33 by means of a kerfed stud 45 having a threaded shank 45^a threaded into the bore 35 in the tang 34. In its under-face, the stud 45 is provided with a threaded bore 46 and 15 snugly fits within an upwardly-opening pocket 47 formed in the upper-face of the forestock 23. Threaded into the bore 46 of the stud 45 is the upper end of a coupling-screw 48 having its head seated in a shouldered bushing or escutcheon 49 20 which, in turn, is mounted in the forestock 23.

As thus constructed and arranged, the stud 45 not only serves to bind the forestock-retainer 43 to the forestock-shoe 33, but also serves in conjunction with the coupling-screw 48 to secure the 25 said forestock-shoe and forestock-retainer to the forestock 23 itself. From the foregoing, it will be apparent that the forestock 23 and its associated parts are firmly but releasably secured to the under-side of the barrel 22.

30 The barrel-unit comprising in the main the parts 22 and 23 may be detached or separated from the butt-unit comprising in the main the parts 20 and 21, by first prying the forestock-unit loose from the under-side of the barrel 22. The 35 detachment of the forestock-unit may be effected by drawing downwardly upon the same to disengage the forestock-retainer 43 from the retaining-lug 44.

After the forestock-unit has been detached 40 from the barrel 22, as just above described, the said barrel, after first being tilted downwardly into the position in which it is shown in Fig. 2, may be moved relatively rearwardly with respect to the frame 20 to thereby disengage the semi-circular notch 30 of its lug 25 from the fulcrum-pin 31, and thus permit the complete separation 45 of the barrel-unit from the butt-unit.

The complementary opposite side-walls 26 and 27 of the frame 20 are respectively notched as at 50 50 and 51 to provide each of the said side-walls with a rearwardly-and-upwardly-facing stop-

abutment 52. The said notches 50 and 51 respectively receive the stop-fingers 38-38 of the forestock-shoe 33.

When the firearm is broken down or opened by 5 tilting the barrel-unit downwardly with respect to the butt-unit, so that the parts are moved from the position in which they are shown in Fig. 1 to the position in which they are shown in Fig. 2, the stop-abutments 39 of the stop-fingers 38-38 10 will engage respectively with the stop-abutments 52-52 of the notches 50 and 51, thus serving to effectively limit the breakdown movement of the firearm-units with respect to each other.

As thus constructed and arranged, the breakdown movement of the firearm-units is limited 15 in a simple, reliable and effective manner and at a low cost for manufacture, by providing one or more stop-abutments upon the forestock-shoe as herein shown and described. The coaction of the stop-abutments 39-39 with the stop-abutments 20 52-52 serve to prevent the under-surface of the barrel 22 from striking the upper-surface of the front-wall 29 of the frame 20 and thus prevent the said barrel from possible distortion.

The invention may be carried out in other specific ways than that herein set forth without departing from the spirit and essential characteristics of the invention, and the present embodiment is therefore to be considered in all respects as illustrative and not restrictive, and all changes 25 coming within the meaning and equivalency range of the appended claim are intended to be embraced therein.

I claim:

A breakdown-firearm including in combination: a butt-unit including a buttstock and a frame, the said frame having a forward portion of U-shaped form in cross-section and having spaced-apart side walls, each of the said side walls being notched to provide a stop-abutment; and a barrel-unit pivoted to the frame of the said butt-unit and having a forestock and a forestock-shoe carried by the said forestock, the said forestock-shoe being provided on each of its respective opposite sides with a stop-finger entered into the notches in the side walls of the said frame and engaging with the stop-abutments thereof to limit the relative movement of the two said units when the same are moved into their breakdown positions.

GEORGE S. LEWIS.
